(57) **CLAIM**

The ornamental design for a combined positron emission tomography and computed tomography, as shown and described.

DESCRIPTION

FIG. 1 is a perspective view of a combined positron emission tomography and computed tomography showing my new design;

FIG. 2 is a front side view of the combined positron emission tomography and computed tomography shown in FIG. 1; FIG. 3 is a rear side view of the combined positron emission tomography and computed tomography shown in FIG. 1; FIG. 4 is a right side view of the combined positron emission tomography and computed tomography shown in FIG. 1; FIG. 5 is a left side view of the combined positron emission tomography and computed tomography shown in FIG. 1; FIG. 6 is a top view of the combined positron emission tomography and computed tomography shown in FIG. 1; and, FIG. 7 is a bottom view of the combined positron emission tomography and computed tomography shown in FIG. 1. The portions of the combined positron emission tomography and computed tomography shown in broken lines form no part of the claimed design.
